UNITED STATES PATENT OFFICE.

ANDREW FORSTER, OF COWES, ISLE OF WIGHT, ENGLAND, ASSIGNOR TO J. SAMUEL WHITE & COMPANY LIMITED, OF EAST COWES, ISLE OF WIGHT, ENGLAND, A COMPANY OF GREAT BRITAIN.

DISTRIBUTING VALVE FOR STEAM ENGINES.

Application filed October 11, 1921. Serial No. 507,090.

To all whom it may concern:

Be it known that I, ANDREW FORSTER, a subject of the King of England, and residing at Cowes, Isle of Wight, England, have 5 invented certain new and useful Improvements in Distributing Valves for Steam Engines, of which the following is a specification.

This invention relates to distributing 10 valves of the compound type for steam engines and has particular reference to valves which comprise a main valve with a curved face adapted to reciprocate over a similarly curved chest face, and an auxiliary valve 15 working upon or in the main valve in a path at right angles to that of the main valve.

In valves of this type the main valve reciprocates after the manner of a shuttle, thus controlling the supply of steam to the engine 20 cylinder, the auxiliary valve controlling the supply of steam to the main valve and cooperating with the latter in controlling the main steam ports.

As at present made the curved port faces 25 are subjected to excessive wear since the back or surface of the main valve remote from the main ports is always exposed to the full steam pressure. Hence the piston-like ends of the main valve soon fail to fit their cylinders and although floating bells have been 30 proposed to overcome this drawback the construction is complicated and the one-sided pressure on the valve remains.

The object of this invention is to provide 35 a valve of the above type in which all the moving parts are balanced thus reducing the wear and distortion due to unequal pressure. A further object of this invention is to provide a valve which can be moved by hand if 40 desired prior to the engine being started or while it is in operation and to furnish a positive indicator showing the position of the valves at any point in the stroke of the engine.

45 According to this invention a balanced reciprocating steam-actuated main valve carries a balanced auxiliary valve within it, the axes of the two valves being at right angles and the auxiliary valve being adapted both 50 to reciprocate within the main valve and to oscillate.

In the preferred construction the main valve is of the shuttle type and comprises an approximately hollow cylindrical member

having a piston face at either end and provided with ports which control the main steam ports formed in a cylindrical bore in the steam chest within which the main valve is reciprocated. Formed within the main valve at right angles to its longitudinal axis 55 is a ported cylindrical bore within which works the auxiliary valve. The auxiliary valve comprises a hollow ported cylindrical member which is mechanically reciprocated within its bore in the main valve and is also 60 oscillated about its own axis by the reciprocation of the main valve. The auxiliary valve controls the supply of steam which effects the reciprocation of the main valve and cooperates with the main valve in controlling 65 the admission of steam to the main ports. As the live steam first enters the interior of the cylindrical auxiliary valve and thence passes to the interior of the cylindrical main valve, it will be seen that both 70 these valves are balanced and not subject to unequal pressure and consequent wear, while further, the manufacture of the steam chest and its valve is greatly simplified and its 75 assembly facilitated.

80 Formed in the main valve, preferably opposite the ports which cooperate with the main ports in the chest face, are supplementary ports through which live steam can be admitted into the interior of the main valve 85 when by-pass valves mounted on the exterior of the steam chest are opened.

These valves are opened, as for instance when starting up, and when opened, although the auxiliary valve cuts off steam 90 at about three-quarter stroke, full pressure steam will flow from the interior of the main valve through the main ports into the engine cylinder to complete the stroke.

The accompanying drawings show by way 95 of example one construction of valve according to this invention, this arrangement being particularly suitable for application to a marine auxiliary engine. In these drawings,

100 Figure 1 is a transverse section through the valve chest showing the operating link, and the auxiliary valve in central vertical section.

Figure 2 is a longitudinal section taken on 105 the line 2-2 of Fig. 1 showing the main shuttle valve in one extreme position.

Figure 3 is a similar view showing the

valve in the other extreme position, exterior portions of the mechanism being omitted, and

5 Figure 4 is a perspective view, on an enlarged scale, of the auxiliary or pilot valve.

Fig. 5 is an elevation of a conventional engine with the valve and operating mechanism.

10 The steam distributing chest is provided with a cylindrical bore having end plates A¹ constituting a closed cylinder A. Communicating with the cylinder so formed is a port B leading to the exhaust and ports C C¹, communicating respectively with the two 15 ends of the engine cylinder in the usual manner. Working within the cylinder A is a hollow cylindrical valve E having a piston face at either end and adapted to reciprocate after the manner of a shuttle. This cylindrical valve E constitutes the main valve and is provided with two ports D D¹ which 20 communicate with the interior of the valve, a recess D² being formed along the centre of the valve whereby either of the steam 25 ports C C¹ may be placed in communication with the exhaust port B after the manner of an ordinary slide valve.

30 Formed within the main valve E at right angles to the longitudinal axis thereof is a cylindrical bore or housing F provided with two ports F¹ F² through which steam is admitted to the interior of the main valve and also having two small ports G G¹ which communicate with passages E¹ E² respectively leading through the piston face at each 35 end of the main valve E into the cylindrical chamber A in which this valve reciprocates. An exhaust port G³ leading to the ports B, C, C¹ in the chest face is formed in the wall 40 of the bore between the two small ports communicating with the passages E¹ E².

45 The reciprocation of the main valve E is effected by admitting steam through one of the ports G G¹ and passages E¹ E² into the space between one end of the main valve cylinder A and its respective piston face, exhaust steam being at the same time permitted to escape through the other small 50 passage from the opposite end of the main valve cylinder through the exhaust port G³ formed in the transverse bore.

55 The supply of steam to effect this reciprocation of the main valve E is controlled by the auxiliary valve which comprises a hollow cylindrical member H into the interior of which live steam flows constantly through openings H¹, the valve being adapted to be reciprocated within the bore F of the main valve in a path at right angles to the main 60 valve and the auxiliary valve being further adapted to oscillate about its own axis when the main valve reciprocates.

65 The auxiliary valve H performs two functions—it controls the supply of steam to effect the reciprocation of the main valve E

and also controls the supply of live steam to the interior of the main valve thus co-operating with the main valve in controlling the supply of live steam to the engine cylinder.

To perform its first function the face of the auxiliary valve adjacent the small ports G G¹ in the main valve is recessed as at J and the ends thereof are also recessed as at J¹ so that as the valve H moves within its cylinder F it admits live steam to one of the ports G G¹ and places the other in communication with the exhaust through the port G³. The recess J is so shaped and dimensioned (see Figure 4) to allow for the 70 oscillating movement of the valve H as it reciprocates.

To control the supply of steam to the main ports C C¹ in the chest face, the auxiliary valve H is provided with two ports K K¹ 75 adapted to open or close the corresponding ports F¹ adapted to open or close the corresponding ports F¹ F² respectively formed in the bore F and communicating through the interior of the main valve with the main 80 ports D D¹ formed therein. The arrangement is such that the ports K and K¹ are only open for the passage of steam to the 85 interior of the main piston valve when their respective ports C¹ and C are open. Thus, 90 when either of the ports C or C¹ is closed its respective port K¹ or K is also closed so that no pressure exists within that end of 95 the main piston valve.

The auxiliary valve H is reciprocated 100 mechanically, a rod L by which this reciprocation is imparted being disposed eccentric to the axis of the auxiliary valve. At its lower end the auxiliary valve is provided with a stem H² bored transversely to the axis of the valve and adapted to carry the free end of a lever L¹ whose other end is keyed to the valve-actuating rod L, the arrangement being such that when the main valve reciprocates, both the auxiliary valve H and its actuating rod L are caused to oscillate, the free end of the lever L¹ sliding in the bore of the valve stem H² as the valve oscillates. The actuating rod L is 105 suitably mounted or constructed so as to turn about its own axis as well as to reciprocate and keyed to a portion of the rod which extends outside the steam chest is a short handle or lever M by which the rod can be manually operated, this lever also 110 serving as a positive means for indicating the position of the pilot valve and therefore 115 of the main valve within its bore.

The operation of the valve is as follows:— 120 Assuming the engine piston is descending, when it has performed about half its stroke, the auxiliary valve H begins to move cutting off the admission of steam to the interior of the main valve E at about three-quarter stroke by closing the steam admis- 125

sion ports in the transverse bore F. Further movement of the auxiliary valve H admits steam to the end 2 of the main valve cylinder through the conduit E² and places 5 the end 1 of the main valve cylinder in communication with the exhaust port B through the corresponding small conduit E¹. The shuttle or main valve E is thus reciprocated being thrown over to the end 1 of the valve 10 chest as shown in Figure 2, simultaneously oscillating the auxiliary valve H which therefore opens the admission port F² in the transverse bore supplying the control of live steam to the bottom of the engine 15 cylinder and simultaneously placing the top of the engine cylinder in communication with the exhaust B. On the reverse stroke (shown in Figure 3) the auxiliary valve and the main shuttle valve are operated in 20 a similar manner, cutting off steam to the bottom of the engine piston through the opposite port F¹ in the transverse bore at about three-quarter stroke.

For starting up where it is necessary to 25 supply full pressure steam for the entire stroke, by-pass valves communicating with the opposite side of the main valve cylinder to the exhaust port B and admission ports C C¹ are opened, these valves, which are indicated at N when opened serving to supply full pressure steam to the interior of the main valve through ports N¹ formed in the face of the valve adjacent to the by-pass openings. It is thus possible for full pressure 30 steam to enter the engine cylinder throughout an entire stroke after the normal supply of full pressure steam has been cut off by the movement within the transverse bore F of the auxiliary valve H.

40 The rod L by means of which the auxiliary valve is moved receives its movement through a lever O operated as shown by the main piston rod P and the lever M keyed to the rod L not only enables the auxiliary valve to be reciprocated by hand so that at any time before or during the operation of the engine the free movement of the valve can be adjusted, but further by rocking this hand lever the main valve can also 45 be reciprocated. It is thus possible at any time to operate either of the valves manually and further by observing the lever M when the engine is in operation a positive indicator is provided showing at any 50 moment the position which either of the valves occupies.

It will be appreciated that a steam distributing valve made in accordance with this invention can be easily constructed since 55 both main and auxiliary valves can be formed almost exclusively by turning operations. Further the construction of the steam chest is simplified and only one stuffing box is required namely that through which the auxiliary valve actuating rod passes.

It is to be understood that the constructional details may be varied considerably without departing from this invention and that the actuating mechanism employed will vary in accordance with the type of engine 70 to which the valve is applied.

What I claim as my invention and desire to secure by Letters Patent is:—

1. In a distributing valve for steam engines the combination with a steam chest 75 having steam and exhaust ports therein, a balanced main piston valve adapted to reciprocate within the chamber and control said ports, a balanced auxiliary valve mounted within the main valve and adapted 80 to reciprocate at right angles to the path of the main valve and also to oscillate about its own axis so as to control the supply of steam to the main valve, and means for reciprocating the auxiliary valve as set 85 forth.

2. In a distributing valve for steam engines the combination of a chamber having steam and exhaust ports therein communicating with the engine cylinder, a hollow 90 ported cylindrical main piston valve adapted to be reciprocated by steam within the chamber, a ported cylindrical chamber formed within the main valve, a hollow cylindrical ported auxiliary valve controlling 95 the supply of steam to the main valve mounted in said cylindrical chamber and adapted to oscillate about its own axis under the reciprocating movement of the main valve, and means for reciprocating the auxiliary valve within the main valve in a path at right angles to that of the main valve as set forth.

3. In a distributing valve for steam engines the combination of a steam chest having a cylindrical bore therein communicating with the main cylinder ports, a substantially hollow ported cylindrical steam-actuated piston valve adapted to reciprocate therein, said piston valve also having a ported transverse cylindrical bore formed in it, a hollow auxiliary valve mounted in said transverse bore and adapted to control the supply of steam to the piston valve and main cylinder ports and means for reciprocating said auxiliary valve at right angles to the path of the piston valve, said means permitting the auxiliary valve to oscillate about its own axis under the reciprocation of the main valve as set forth.

4. In a distributing valve for steam engines the combination of a steam chest having a cylindrical bore therein communicating with the main cylinder ports, a substantially hollow ported cylindrical piston valve having a piston face at each end adapted to be reciprocated by steam within said cylindrical bore, said piston valve also having a ported transverse cylindrical bore formed in it, a hollow ported auxiliary 125

- valve mounted in said transverse bore and adapted to control the supply of steam to the piston valve and main cylinder ports, an actuating rod connected to the auxiliary valve extending through the steam chest and means for reciprocating said rod, said means permitting the auxiliary valve to oscillate about its own axis under the reciprocation of the main valve as set forth.
5. In a distributing valve for steam engines the combination of a steam chest having a cylindrical bore therein communicating with the main cylinder ports, a substantially hollow ported cylindrical piston valve having a piston at each end adapted to be reciprocated by steam within said cylindrical bore, said piston valve also having a ported transverse cylindrical bore formed in it, a hollow auxiliary valve mounted in said transverse bore and having openings through which steam is constantly admitted to the interior of said auxiliary valve, and means for reciprocating the auxiliary valve within its bore at right angles to the path of the piston valve so as to control the supply of steam to the interior of the piston valve and through the ports therein to the main cylinder ports, said means also permitting the auxiliary valve to oscillate about its own axis under the reciprocation of the main valve as set forth.
10. 5. In a distributing valve for steam engines the combination of a steam chest having a cylindrical bore therein communicating with the main cylinder ports, a substantially hollow ported cylindrical piston valve having a piston at each end adapted to be reciprocated by steam within said cylindrical bore, said piston valve also having a ported transverse cylindrical bore formed in it, a hollow auxiliary valve mounted in said transverse bore and having openings through which steam is constantly admitted to the interior of said auxiliary valve, and means for reciprocating the auxiliary valve within its bore at right angles to the path of the piston valve so as to control the supply of steam to the interior of the piston valve and through the ports therein to the main cylinder ports, said means also permitting the auxiliary valve to oscillate about its own axis under the reciprocation of the main valve as set forth.
15. 5. In a distributing valve for steam engines the combination of a steam chest having a cylindrical bore therein communicating with the main cylinder ports, a substantially hollow ported cylindrical piston valve having a piston at each end adapted to be reciprocated by steam within said cylindrical bore, said piston valve also having a ported transverse cylindrical bore formed in it, a hollow auxiliary valve mounted in said transverse bore and having openings through which steam is constantly admitted to the interior of said auxiliary valve, and means for reciprocating the auxiliary valve within its bore at right angles to the path of the piston valve so as to control the supply of steam to the interior of the piston valve and through the ports therein to the main cylinder ports, said means also permitting the auxiliary valve to oscillate about its own axis under the reciprocation of the main valve as set forth.
20. 5. In a distributing valve for steam engines the combination of a steam chest having a cylindrical bore therein communicating with the main cylinder ports, a substantially hollow ported cylindrical piston valve having a piston at each end adapted to be reciprocated by steam within said cylindrical bore, said piston valve also having a ported transverse cylindrical bore formed in it, a hollow auxiliary valve mounted in said transverse bore and having openings through which steam is constantly admitted to the interior of said auxiliary valve, and means for reciprocating the auxiliary valve within its bore at right angles to the path of the piston valve so as to control the supply of steam to the interior of the piston valve and through the ports therein to the main cylinder ports, said means also permitting the auxiliary valve to oscillate about its own axis under the reciprocation of the main valve as set forth.
25. 5. In a distributing valve for steam engines the combination of a steam chest having a cylindrical bore therein communicating with the main cylinder ports, a substantially hollow ported cylindrical piston valve having a piston at each end adapted to be reciprocated by steam within said cylindrical bore, said piston valve also having a ported transverse cylindrical bore formed in it, a hollow auxiliary valve mounted in said transverse bore and having openings through which steam is constantly admitted to the interior of said auxiliary valve, and means for reciprocating the auxiliary valve within its bore at right angles to the path of the piston valve so as to control the supply of steam to the interior of the piston valve and through the ports therein to the main cylinder ports, said means also permitting the auxiliary valve to oscillate about its own axis under the reciprocation of the main valve as set forth.
- auxiliary and piston valves within their casing as set forth.
6. In a distributing valve for steam engines the combination of a steam chest having a cylindrical bore therein communicating with the main cylinder ports, a substantially hollow ported cylindrical steam-actuated piston valve adapted to reciprocate therein, said piston valve also having a ported transverse cylindrical bore formed in it, a hollow ported auxiliary valve mounted in said transverse bore and having openings through which steam is constantly admitted to the interior of said auxiliary valve, and means for reciprocating the auxiliary valve within its bore at right angles to the path of the piston valve so as to control the supply of steam to the interior of the piston valve and through the ports therein to the main cylinder ports, said means also permitting the auxiliary valve to oscillate about its own axis under the reciprocation of the main valve as set forth.

In testimony whereof I have signed my name to this specification.

ANDREW FORSTER.
